UNITED STATES PATENT OFFICE.

JOHN T. BURT, OF EAST STROUDSBURG, PENNSYLVANIA.

DESIGN FOR A FRAME FOR BOTTLE-OPENERS.

SPECIFICATION forming part of Design No. 25,608, dated June 9, 1896.

Application filed March 6, 1896. Serial No. 582,147. Term of patent 7 years.

To all whom it may concern:

Be it known that I, JOHN T. BURT, a citizen of the United States, residing at East Stroudsburg, Pennsylvania, have invented and produced a new and original Design for Frames of Bottle-Openers, of which the following is a specification.

In the accompanying drawings, Figure 1 is a side elevation showing the design, and Fig. 2 is a front view.

The leading feature of the design consists in a base with the curved arm extending therefrom and overhanging the base, the said curved arm extending backward, upward, and inward on one side only of the base and having a socket or eye at its inner upper end.

In the drawings, A represents the base, and from this base extends upwardly the curved arm, the upper end extending horizontally and overhanging the center of the base. The straight part of the upwardly-extending arms has lateral projections thereon.

What I claim is—

The design for a bottle-opener frame herein shown and described. 25

In testimony whereof I affix my signature in presence of two witnesses.

JOHN T. BURT.

Witnesses:

FRANK M. VANWHY,
WILLIAM H. BURT.
